UNITED STATES PATENT OFFICE.

JOSEPH MCGUIRE, OF PHILADELPHIA, PENNSYLVANIA.

COMBINED SHAVING-BRUSH AND SOAP-HOLDER.

1,358,565.

Specification of Letters Patent.

Patented Nov. 9, 1920.

Application filed December 26, 1919. Serial No. 347,353.

To all whom it may concern:

Be it known that I, JOSEPH MCGUIRE, a citizen of the United States, and a resident of Philadelphia, in the county of Philadelphia and State of Pennsylvania, have invented a new and Improved Combined Shaving-Brush and Soap-Holder, of which the following is a full, clear, and exact description.

10 This invention relates to combination toilet articles for men's use.

Among the objects of the invention is to provide a combined shaving brush and soap holder of a most compact and convenient 15 nature making the device especially useful to a traveling man or any other whose packing or storing facilities are limited.

More specifically the improvement embodies a shaving brush having a telescopic 20 handle providing for ample length for use of the brush and yet assuring a minimum volume or length when in idle position. Coöperating with the brush is a container for the purpose of keeping the brush clean 25 and sanitary when not in use, and serving at the same time as a soap holder and ejector assuring that the soap may be used most conveniently and economically until the last particle of the soap is used.

30 With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same 40 parts in the several views, and in which—

Figure 1 is a side elevation of my combined device in closed and collapsed form.

Fig. 2 is a vertical sectional view of the same.

45 Fig. 3 is a detail sectional view of the soap holder cap.

Fig. 4 is a vertical sectional view of the plunger barrel indicating its relation to the soap holder as when in use.

50 Fig. 5 is a side elevation of the brush with its telescopic handle in section and extended for practical use.

Fig. 6 is a plan view.

55 Referring now more specifically to the drawings I show my improved combined device as comprising a shaving brush 10

cemented or otherwise permanently fixed in a base 11 which may readily be made from sheet metal of uniform thickness and formed with a spiral thread on its surface. 60 The formation of this thread makes most effective the cementing or other means for securing the body of bristles in the base.

Coöperating with the base 11, which except for the aforesaid screw thread is of 65 cylindrical form, is a handle comprising a tubular shell 12 which like the base 11 is preferably made of sheet metal and so designed as to have a screw thread formed thereon from one end to the other and on 70 both the inner and outer surfaces. To one end of the shell is permanently fixed a knob 13 constituting a finger piece for the manipulation of the shell and brush and also acting as a closure for the tubular shell. 75 This knob may be made of any suitable material of a rigid nature and constitutes a permanent fixture upon the shell. The otherwise open end of the shell is adapted to receive the base 11 of the brush, the threads 80 of the several members coöperating with each other as will be readily understood from the drawings.

14 indicates a soap holder and is preferably made as a cylinder open at both ends 85 but provided with a screw thread from one end to the other. Any suitable form of soap such as a stick S may be carried in this holder 14, the main portion of the soap being carried within the holder, but with a 90 suitable portion projecting therefrom for use upon the face in a manner well understood by men who shave themselves. Coöperating with this soap holder is a closure cap 15 adapted to cover the otherwise exposed end of the soap while the threaded portion 15' of the cap is adapted to screw upon the outside of the upper end of the holder 14 as shown in Figs. 1 and 2. Only a portion of the rim of the cap is threaded 95 whereby it is assured that the cap may be screwed upon the holder with sufficient tightness to prevent accidental loosening of the cap.

At 16 I show a plunger barrel serving several important functions as follows: First, this member has a closed end 17, a screw threaded cylindrical body, and a smooth open end at 18. The thread formed on the member 16 is designed to receive in it the 110 handle shell 12. Assuming that the brush base 11 is screwed well down toward the

closed end 13 of the handle the body of bristles 10 may be projected directly into the barrel 16 and then by rotation of the handle shell within the barrel the handle will be 5 not only collapsed in the shortest possible form, but also will be neatly housed within the barrel, the cap or knob 13 of the handle serving as a neat finish or closure for the otherwise open end 18 of the barrel and 10 against which the flared end portion 13' of the knob is adapted to bear directly and with sufficient friction to insure that no accidental loosening of the parts will take place. The contact between the base 11 and 15 the shell 12 may be relatively loose along the threads and yet no inconvenience will result because the brush is well and reliably housed within the barrel 16 except when in use. The abutting of the cap or knob 13 20 against the end 18 of the barrel will insure sufficiently tight grip between these parts even though the threading action may be relatively easy.

The flat closed end 17 of the barrel constitutes the barrel into a plunger for forcing 25 the bar of soap S outward from the soap holder from time to time as may be required as a result of the wearing down of the exposed end of the soap. The soap from its 30 nature may be fitted in the holder fairly tightly and will not drop out under any ordinary circumstances. The action of the plunger against the soap will always insure a relatively tight grip between the holder 35 and the exterior surface of the plunger barrel. Therefore no looseness or inadvertent relative movement between these two parts is liable to take place.

The device made also entirely of relatively thin sheet material may be manufactured very cheaply and yet of a most durable and efficient nature, and with ordi-

nary care will last indefinitely. When one bar of soap is completely used by being successively projected from the holder the plunger will be retracted and a fresh bar may be inserted. 45

I claim:

1. In a combined shaving brush and soap holder, a soap holder having an internal 50 screw thread, a brush having a handle with external and internal screw threads, the base of the brush having external and internal screw threads, the latter for telescopic co-operation with the internal thread of the 55 handle and a plunger barrel serving as a casing for the brush and a plunger to deliver the soap from the holder, said plunger barrel being provided with an internal screw thread to receive the external thread of the 60 handle and with an external thread for co-operation with the internal thread of the soap holder.

2. In a combined device of the class set forth, the combination of a barrel having 65 one end closed and the other end open and provided intermediate of its ends with an internal screw thread, a brush whose handle comprises a base with an external 70 screw thread and a shell with an internal screw thread for co-operation with the base thread and an external screw thread for co-operation with the internal thread of the barrel into which barrel the brush is adapted to be nested 75 when the brush base is adjusted far into the handle shell, and a knob serving to close the otherwise open end of the shell and adapted to abut against the open end of the barrel, said knob having a flaring edge for 80 frictional co-operation with said open end of the shell, substantially as set forth.

JOSEPH McGuIRE.
